UNITED STATES PATENT OFFICE

WILLIAM SCRIMGEOUR, OF WASHINGTON, DISTRICT OF COLUMBIA

FUEL BURNER

Application filed January 19, 1926. Serial No. 82,337.

This invention relates to fuel burners and particularly to a burner for the combustion of heavy or non-volatile fuel such as kerosene distillates and fuel oils.

5 In burning non-volatile oil by heating the same to form a gas and then causing the gas to entrain the air necessary for combustion, as in a Bunsen burner, the operation is characterized by a roaring which is very objectionable in any installation and particularly in burners for domestic use. It has been proposed to mechanically atomize non-volatile fuel by or into a stream of low pressure air but burners of this type are open to the objection that the vaporization of the fuel is not complete and carbon deposits accumulate in the burner.

10

15

In accordance with the present invention
20 efficient and substantially noiseless combustion
of non-volatile fuel is obtained by injecting
a spray of liquid fuel under high pressure
into a quantity of air insufficient for complete
25 combustion, burning a small portion of the
fuel to provide heat for the vaporization of
the remaining part, then passing the vaporized
30 fuel mixture into a body of air sufficient
to support complete combustion. The
quantity of heat furnished by the partial
burning of the rich mixture may be sufficient
35 to transform the fuel into a permanent
gas or it may be sufficient only to vaporize
the fuel. In any event, the liquid fuel is
made available for combustion by heating
the same with a limited quantity of air, and
35 not solely by mechanical atomization.

An object of the invention is to provide an improved method and apparatus for effecting the quiet and efficient combustion of liquid fuel which is non-volatile at atmospheric temperatures. An object is to provide a method of burning non-volatile fuel by which a rich fuel mixture is partially burned to provide heat for the vaporization of the bulk of the fuel. An object is to provide a method of burning fuel in which a rich and burning fuel mixture is caused to travel in a spiral path in one plane and from which path the vaporized mixture is withdrawn in a direction normal to the plane of the path for mixture with a larger quantity of combustion supporting

air. The invention has for other objects the provision of apparatus capable of carrying out the novel method of combustion and particularly apparatus having a vaporizing chamber in which a rich fuel mixture is delivered for partial combustion and from which the vaporized mixture passes into engagement with additional air and is completely burned. A further object of the invention is to provide a vaporizing chamber of spiral shape from which the vaporized mixture passes in a direction normal to the plane of the spiral. More specifically, an object is to provide a burner having side walls which define a spirally-shaped vaporizing chamber into which a rich fuel mixture is introduced for partial combustion, a top wall provided with an outlet opening or openings adjacent the axis of the spiral and with a passage for delivering additional air to the burning mixture as it escapes from the vaporizing chamber. These and other objects of the invention which will be apparent from the following description may be attained by the embodiment of my invention which is illustrated in the accompanying drawings in which,

Fig. 1 is a plan view of the burner and a portion of the air supplying conduit;

Figs. 2, 3 and 4 are vertical sections through the burner as taken on the respective section lines 2-2, 3-3, and 4-4, of Fig. 1; 80

Fig. 5 is a horizontal section through the burner on line 5-5 of Fig. 4; and

Fig. 6 is a fragmentary vertical section illustrating a modified form of air directing nozzle. 85

In the drawings, the reference character A indicates the burner head generally, the character B the air supply conduit and the character C indicates the fuel pipe. The burner head comprises a bottom wall 10, a top wall 11 of annular shape and a false bottom wall 12 of spiral shape. The top and bottom walls are joined by an outer wall 13, and the top wall 11 and the false bottom wall 12 are joined by an inner cylindrical wall 14 which cooperates with the walls 11, 12 and 13 to form a spirally-shaped vaporizing chamber 15. The outer side wall 13 is approximately circular in section but is incomplete to provide

a tangentially arranged opening 16 for the introduction of the fuel and air. As best shown in Fig. 5, the opening 16 is arranged for the introduction of the fuel at the widest part of the spiral chamber defined by the eccentrically arranged outer wall 13 and inner wall 14. A supporting plate 17 is arranged between the opening 16 and the end of the air conduit B, which supporting plate carries the air directing nozzle 18. The fuel nozzle 19 is mounted on and centrally of the air nozzle 18 and is connected in any suitable manner with the fuel pipe C. The nozzle 19 is provided with a small outlet 20 through which liquid fuel under high pressure is directed into and tangentially of the spiral vaporizing chamber 15. The nozzle 19 and outlet 20 are so constructed that the high pressure oil enters the chamber in the form of a fine spray or mist. The air directing nozzle 18 is provided with a passage or passages 21 for introducing a limited quantity of air into the chamber 15 and around the spray of liquid fuel. The nozzle proper of the air directing device 18 is provided by a short cylindrical wall 22 which directs the air flowing through the openings 21 into the chamber 15 in a tangential direction.

The air and fuel inlet nozzle 18 lies in line with or to the rear of the adjacent portion 13' of the outer wall 13 of the spiral vaporizing chamber. This arrangement results in a relatively long line of travel from the oil nozzle to the portion of the wall 13 which extends transversely of the axis of the fuel nozzle, and it prevents the residual portion of the fuel stream which re-enters the wide portion of the spiral path from sweeping across the fuel nozzle and spark gap. Air passages 23 in the plate 17 permit the introduction of an additional quantity of primary air.

The rear face of the nozzle 18 is provided with a yoke 24 for receiving a spark plug S, which spark plug is retained in operative position by a set screw 25. The spark gap 26 of the spark plug is arranged in line with and close to the fuel outlet 20 of the nozzle 19.

The top 11 is preferably bent upwardly around the inner wall 14 and is provided with an opening or openings 27 for permitting the passage of the fuel mixture from the vaporizing chamber. As illustrated, a plurality of annularly arranged openings 27 are provided, which openings are symmetrically disposed with respect to the inner wall 14, that is, with respect to the axis of the spiral vaporizing chamber 15.

The supply of secondary air in quantity sufficient to complete the combustion of the fuel is passed into the air chamber 28 formed between the bottom 10 and the false bottom 12 through an opening 29 in the plate 17. A stud 30 which is arranged axially of the spiral vaporizing chamber 15 and the inner wall 14 is secured to the bottom wall 10 and

carries a deflector 31 at its upper end. The lower face 32 of the deflector 31 has the form of an upwardly flared cone, except at the central portion thereof, which is provided with a downwardly directed flange 33. The deflector 31 is threaded upon and therefore adjustable along the stud 30 to permit the regulation of the quantity of secondary air which is delivered to the burner. The quantity of air may also be regulated, if desired, by turning the wall 14, which is threaded in the false bottom 12, to adjust the position of the top of the wall 14 with respect to the level of the top wall 11.

The false bottom 12 slopes toward a drain 80 opening 34 which communicates with the drain pipe 35 for permitting the escape of any unvaporized fuel which might accumulate in the vaporizing chamber if the fuel fails to ignite.

As shown in Fig. 6, the air nozzle 18' may be provided with forwardly converging walls 22' for increasing the velocity at which the air is introduced into the vaporizing chamber.

The operation of the burner is as follows:

In accordance with the usual practice the liquid fuel and the air are supplied under pressure from suitable sources, such as an oil pump and a centrifugal blower, respectively. 95 As the burner does not depend upon the velocity of the air stream for the vaporization of the fuel, the air is supplied through conduit B at a relatively low pressure. The pressure in the fuel supply pipe C is relatively high, however, as the fuel is to be projected into the vaporizing chamber as a fine spray. To place the burner in operation the fuel pump and blower are started and the ignition circuit is closed through the spark plug S. 100

The spark gap 26 ignites the fuel but the quantity of air supplied through the openings 21 is such that the point of ignition of the fuel stream is blown forwardly to a point in advance of the spark gap. The primary air entering through the openings 21 and 23 is insufficient to support complete combustion of the fuel and is moving at relatively slow velocity. A portion of the fuel will burn to supply heat for the vaporization of the bulk of the fuel but the quantity of fuel burned in the vaporizing chamber is comparatively small. As the burning fuel mixture is deflected along the spiral path defined by the chamber 15, the kinetic energy due to 110 the velocity of the stream in a horizontal direction is dissipated and the burning mixture of vaporized fuel and air passes out of the horizontal path and through the burner openings 27. The spiral shape of the vaporizing chamber is an important feature of the invention, since the travel of the burning stream along this path results in a substantially uniform upward pressure at the top wall 11 adjacent the inner wall 14 of the 115

120

125

130

spiral chamber. As the upward pressure is substantially uniform the burning mixture passes through the openings 27 in uniform quantities to produce a symmetrical flame by combining with the secondary air which is supplied through the central passage of the burner. The flame is turned laterally by the deflector 31, which deflector may be adjusted to provide the most efficient combustion. The 10 gas mixture which passes from the vaporizing chamber 15 is of substantially homogeneous composition and the outlet opening, or openings, 27 are so spaced with respect to the secondary air passage that the rich mixture and the secondary air are combined in the 15 proper proportion to secure an even flame around the head of the burner.

As stated above, the point of ignition of the flame is held in advance of the fuel opening 20. In some installations the velocity of the burning stream necessary to secure this result is best obtained by contracting the walls of the air-projecting nozzle, as shown in Fig. 6.

It is to be understood that the invention is not limited to the specific embodiment herein illustrated, since some changes in the relative size of the parts will usually be required when a burner of a given size is to be used for 30 different purposes. For instance, in adapting the burner illustrated for use with a materially greater quantity of fuel, it may be necessary to increase the size of the openings 20, 23, or to increase the number of such 35 openings. If desired, the air passages 21 and 23 may be of such size as to pass the maximum desired quantity of air, and some of the passages may be closed in any suitable manner when the burner is put to a use which requires 40 a relatively small quantity of fuel.

These and many other changes in the several parts, their relative size, shape and location may be made within the scope of my invention as set forth in the following claims.

I claim:

1. The method of burning non-volatile fuel, which comprises projecting liquid fuel into a limited quantity of air, constraining the rich mixture to move along a spiral path 50 of decreasing area in cross-section, igniting the fuel upon its entrance upon said spiral path, delivering the burning rich mixture in a direction normal to the plane of said spiral path, and supplying additional air to said burning rich mixture.

2. The method of burning non-volatile liquid fuel which comprises introducing a spray of liquid fuel into a slowly moving and limited quantity of air, constraining the rich mixture to follow a horizontal spiral path of 60 decreasing cross-section, igniting the fuel at the entrance of said path, delivering the burning rich mixture from said path near the 65 axis thereof and in an upward direction, and

supplying additional air to said burning mixture as it leaves said spiral path.

3. In a liquid fuel burner, a vaporizing chamber having walls defining a horizontally-arranged spiral path, means for establishing a stream of air and fuel traveling along said path and towards the center of the spiral, and outlet means at the top of said chamber adjacent the center of the spiral permitting the 70 passage of the fuel mixture from the chamber.

4. In a burner for non-volatile liquid fuel, a vaporizing chamber having a top, a bottom and inner and outer side walls, said side walls being cylindrical and eccentrically arranged to define a spirally-shaped chamber, means for introducing a stream of fuel and air into and tangentially of said chamber at the widest portion thereof, and an outlet for the fuel mixture through the top wall and adjacent 75 said inner side wall.

5. The invention as claimed in claim 4, wherein the outer side wall at the narrowest portion of the spirally-shaped chamber directs the residual portion of the fuel and air stream into the widest portion of the spiral path along a line lying in advance of the fuel and air supplying means.

6. In a fuel burner, a vaporizing chamber, means for introducing a rich mixture of fuel and air into and horizontally of said chamber, and a plurality of outlet openings in the top of said chamber, said chamber and said outlet means being constructed and arranged to effect the discharge through all of said outlet 95 openings of a fuel mixture which is of homogeneous composition and at substantially 100 uniform pressure.

7. A burner for non-vaporizable liquid fuel comprising a vaporizing chamber, means for delivering liquid fuel and a quantity of air 105 insufficient for the complete combustion thereof into said chamber, means for initiating the combustion of said mixture in said chamber to promote the vaporization of the fuel, outlet means permitting the passage from said 110 chamber of the vaporized fuel mixture, and means for supplying additional air to said mixture as it issues from said chamber, said chamber and said outlet means being constructed and arranged to effect the discharge 115 through all portions of said outlet means of a fuel mixture which is of homogeneous composition and at substantially uniform pressure.

8. In a fuel burner, a vaporizing chamber having a bottom wall, an approximately circular side wall, and a top wall, a vertical air passage extending through said chamber and eccentrically thereof, inlets for introducing fluid fuel and air at the widest portion of the 125 vaporizing chamber and tangentially thereof, and means permitting the passage of intermixed fuel and air through the top wall of said chamber adjacent said air passage.

9. In a fuel burner, a burner head having 130

inner and outer walls approximately circular in horizontal cross-section, said walls being eccentrically arranged to define a spirally-shaped vaporizing chamber, a tangentially arranged opening into said chamber at the 5 widest portion thereof for the introduction of fuel and air, a top wall closing said inlet chamber and having means adjacent the inner wall of said chamber permitting the escape of the fuel mixture therefrom, a false bottom 10 wall joining said inner and outer walls to close said vaporizing chamber, and a bottom wall cooperating with said outer wall to define a secondary air chamber underlying said vaporizing chamber, and a deflector overlying the central opening and the outlet means 15 of said top annular wall.

10. In a burner for non-volatile liquid fuel, a vaporizing chamber having a top, a bottom and inner and outer side walls, said side walls 20 being cylindrical and eccentrically arranged to define a spirally-shaped chamber, means for introducing a stream of fuel and air into and tangentially of said chamber at the widest portion thereof, an outlet for the fuel mixture 25 through said top wall and adjacent the inner side wall, and a deflector positioned above said outlet for laterally directing the mixture issuing from said outlet.

11. The invention as set forth in claim 10, 30 wherein means is provided for vertically adjusting said deflector with respect to said outlet.

12. The invention as set forth in claim 10, 35 wherein a stud is arranged axially of said spirally-shaped chamber, and said deflector is adjustably mounted on said stud.

In testimony whereof, I affix my signature.
WILLIAM SCRIMGEOUR.
